ELECTRICAL CONTROL SYSTEM FOR
LIQUID FUEL BURNERS

Fred B. Aubert, Detroit, Mich.

Application September 18, 1947, Serial No. 774,825

9 Claims. (Cl. 158—28)

1

This invention relates to new and useful improvements in control systems for liquid fuel burners.

One of the objects of this invention is to provide an improved control system for liquid fuel burners.

Another object of this invention is to provide a control system for a liquid fuel burner having controllable fuel vaporization means.

Another object of this invention is to provide a control system for liquid fuel burners which is easily constructed and assembled and inexpensive to manufacture.

Other objects of this invention will become apparent from time to time through the specification and claims as hereinafter recited.

In the accompanying drawings to be taken as a part of this specification, there are clearly and fully illustrated two preferred embodiments of this invention, in which drawings—

Figure 1 is view in vertical cross-section of a pot type liquid fuel burner having a fuel vaporization member and diagrammatically showing a control system therefore, and

Fig. 2 is a view of a burner and fuel vaporization member similar to that in Fig. 1 but having a different control system therefor.

Referring to the drawing by characters of reference, in Fig. 1 there is shown a liquid fuel burner 1 having a pot 2 and a recessed fuel well portion 3. The pot 2 has a plurality of air supply holes 4 therein and is surrounded by an air supply jacket 5 having a cover member 6 and being supplied with air by a blower 7. The fuel well portion 3 opens upward into the pot 2 through an aperture 8 in the lower wall 9. There is a fuel vaporization member 10 positioned in the fuel well portion 3 and extending upwardly into the pot 2. The member 10 has an enlarged hollow end portion 11 and a smaller solid rod portion 12. In commercial construction the fuel well portion 3 and fuel vaporization member 10 would be cylindrical in shape although the burner would function with these members constructed in other shapes. A fuel supply conduit 13 opens into the lower side wall of the fuel well portion 3 through an aperture 14 for supplying fuel for combustion in the burner. The member 10 is operable upon heating to vaporize liquid fuel coming thereagainst for combustion and is of such a size relative to the fuel well portion 3 that a very small annular space is enclosed between the member 10 and fuel well portion 3 so that a large area of heating surface of the member 10 is provided for

2

a small amount of fuel thereby increasing the efficiency of the transfer of heat for vaporizing fuel. Positioned inside the hollow end portion of the fuel vaporizing member 10 for heating the fuel supplied to the fuel well portion 3 prior to combustion is an electrical resistance heater coil 15 carried in an insulating member 16. The rod portion 12 of the fuel vaporizing member 10 extends upward through the pot 2 into the zone of combustion and is operable during combustion to conduct heat to the hollow end portion 11 for the vaporization of fuel. The supply of fuel through the conduit 13 to the fuel well portion 3 is controlled by an electrically controllable valve 17 such as a solenoid valve or a valve operated by an electrically energizable heat motor. The ignition of fuel in the burner pot 2 is accomplished by an electric spark ignition 18 such as a spark plug.

The control system for the burner 1 is supplied with power from a main power source 19 to the primary 20 of a transformer 21. From the secondary 22 of the transformer 21 a conductor 23 leads to the fixed contact 24 of a room thermostat 25. The thermostat 25 is of a conventional type having a fixed contact 24 and a movable contact 26 carried by a bimetallic blade 27. The room thermostat has an electric heater coil 28 which functions as a compensator for fluctuations in temperature to which the thermostat responds. The heater coil 28 is connected by a conductor 29 to a resistor 30 which is in turn connected to the transformer secondary 20 as at 31. From the bimetal blade 27 of the thermostat 25 a conductor 32 runs to the coil 33 of the relay switch 34. The relay switch 34 is a bi-pole switch having two fixed contacts 35 and 36 and two movable contacts 37 and 38 carried by contact arms 39 and 40 respectively, contact arms 39 and 40 being connected to each other for joint movement by a connecting member 41 of an electric insulating material. From the relay coil 33 a conductor 42 runs to a connection point 43 on a conductor 44 which interconnects the fixed contact 35 and the fixed contact 45 of a thermostatic switch 46. The thermostatic switch 46 has three fixed contacts 45, 47 and 48 and three movable contacts 49, 50 and 51. The movable contact 49 is carried by a contact arm 52 and the movable contacts 50 and 51 are carried by a contact arm 53. The contacts 45 and 49, 48 and 51 are initially closed and the contacts 47 and 50 are initially open so that movement of the thermostatic switch 46 will open the closed contacts and close the open contacts. The contact arms 52 and 53

are connected each to each by an actuating member 54 of an insulating material which is in turn connected to and actuated by a bimetallic blade 55. From the contact arm 52 of the switch 46 the conductor 56 connects with a conductor 57 which runs from the relay switch contact arm 39 to the connection point 31 on the transformer secondary 22. From the main power source 19 and connected in parallel with the transformer primary 20 a circuit runs by conductors 58 and 59 to the electric motor 60 which drives the blower 7, the circuit being completed by conductors 61 and 62 back to the main power source 19. This last-mentioned circuit through the blower motor 60 is such that the blower 7 will be operating at all times that the system is energized. From a connection point 63 at the junction of conductors 58 and 59 in the blower motor circuit, a conductor 64 runs to the fixed contact 36 of the relay switch 34. From the contact arm 40 of the relay switch 34 conductors 65 and 66 run to the movable contact arm 53 of the thermostatic switch 46. From the fixed contact 48 of the thermostatic switch 46 a conductor 67 runs to a conductor 68 which is in turn connected to an electrical resistance heater 15, the circuit being completed by a conductor 69 which joins the conductor 62 at a connection point 70 thus completing the circuit back to the main power source 19. A conductor 71 runs from a connection point 72 at the juncture of conductors 67 and 68 to the primary 73 of an ignition transformer 74. The circuit through the ignition transformer 74 is completed back to the main power source 19 by conductors 75 and 76 which connect with the conductor 69 at a connection point 77. The conductor 75 leads to the fixed contact 78 of a thermostatic switch 79, the contacts of the switch 79 being open so that the circuit through the ignition transformer 74 is broken. The thermostatic switch 79 has a fixed contact 78 and a movable contact 80 which is carried by a contact arm 81 from which runs the conductor 76. The switch 79 is actuated by a bimetallic blade 82 having an actuating member 83 of an insulating material connected to the contact arm 81 for movement thereof. From the fixed contact 47 of the thermostatic switch 46 a conductor 84 runs to the electrically controllable valve 17 which is connected by a conductor 85 to a connection point 86 on the conductor 76, the circuit being completed by conductors 76, 69, and 62 back to the main power source. There is a conductor 86^a which runs from a connection point 87 at the junction of conductors 65 and 66 to a terminal point 88 which is connected to the movable contact arm 89 of a gas tube warp switch 90. The gas tube warp switch 90 is of the conventional type having a fixed contact 91 and a movable contact 92 which is carried by a contact arm 89 of a bimetallic thermostatic material and having an ionizing member 93 which functions to heat the gas within the tube to cause the contact arm 89 to warp closing the contacts 91 and 92. The fixed contact 91 of the gas tube warp switch 90 is connected by the conductor 94 to a connection point 95 on the conductor 84 at the valve 17. The ignition transformer secondary 96 is connected by a conductor 97 to the spark electrode 98 of the spark ignition in the pot 2. The ignition transformer secondary 96 is also connected to a pair of inductive coils 99 and 100 which are grounded as at 101. The coil 100 is connected by the capacitor 102 to a connection point 103 on the conductor 97 leading to the ignition electrode 98. 75

The coil 99 is connected to the ionizing electrode 93 in the gas tube warp switch and is operable to actuate the same.

In operation this form of the invention functions as follows:

When current is supplied to the system as from the main power source 19 the transformer 21 is energized for operation and the blower motor 60 is energized by the circuit through the conductors 58, 59, 61 and 62. At this point in the operation the blower 7 is turned on and is supplying air to the space enclosed by the jacket 5 and the burner pot 2 to support combustion in the burner. When the room thermostat 25 closes calling for heat, a circuit is completed from the transformer secondary 22 by conductor 23, the closed contacts 24 and 26 of the thermostat 25, and the conductor 32 to the relay coil 33. The circuit through the relay coil 33 is completed for initial operation through the conductors 42 and 44, the closed contacts 45 and 49 of the thermostatic switch 46 and the conductors 55 and 57 leading back to the transformer secondary 22. When the relay coil 33 is thus energized the movable contacts 37 and 38 close against the fixed contacts 35 and 36 respectively. When contacts 35 and 37 of the relay switch 34 are closed a holding circuit for the relay coil 33 is established through the closed contacts 35 and 37 and the conductor 57 leading back to the transformer secondary 22. When the relay contacts 36 and 38 are closed a circuit is completed by conductors 58 and 64, the closed contacts 36 and 38, the conductors 65 and 66, the closed contacts 43 and 51 of the thermostatic switch 46, and the conductors 67 and 68 through the electrical resistance heater 15 in the hollow end portion 11 of the fuel vaporization member 10, the circuit being completed back to the main power source by conductors 69 and 62. It is thus seen that when the room thermostat 25 closes calling for heat and energizing the relay switch 34 a circuit is completed through the electrical resistance heater 15 for heating the fuel vaporization member 10. The thermostatic switch 79 is positioned adjacent the fuel well portion 3 and is responsive to the temperature of the hollow end portion 11 of the fuel vaporization member 10 which is heated by the electrical resistance heater 15. When the temperature of the fuel vaporization member 10 and end portion 11 reaches a predetermined level, such as that required for vaporization of fuel for initial operation, the bimetal blade 82 will move the contact 89 of the thermostatic switch 79 into engagement with the fixed contact 78. The closing of the contacts 80 and 78 of the thermostatic switch 79 completes a branch circuit from the connection point 72 of the resistance heater circuit by way of conductor 71 to the ignition transformer primary 73 which is connected by conductor 75, the closed contacts 80 and 78, and the conductor 76 to the connection point 77 on the conductor 69 leading back to the main power source. Upon energization of the ignition transformer 74, the spark ignition 18 in the burner pot 2 will begin to function and is operable to ignite fuel vapors with which it comes in contact. Simultaneously with the occurrence of sparks in the burner pot 2 the inductive coils 99 and 100 will operate through the ionizing electrode 93 to heat the gas tube warp switch 90 thereby to close the contacts 91 and 92. When the contacts 91 and 92 of the gas tube warp switch 90 are closed a branch circuit is established through the fuel control valve 17 by

way of conductors 65 and 86^a leading from the relay switch 34 to the gas tube warp switch 90 and conductor 94 leading from the warp switch 90 to the valve 17, the circuit from the valve 17 being completed by conductors 85, 76, 69 and 62 back to the main power source. At this point in the operation of the system the electric heater 15 is energized for the vaporization of fuel, the ignition 18 is energized and the fuel control valve 17 is opened to permit the supply of fuel to the fuel well portion 3. When the fuel supplied to the fuel well portion 3 comes in contact with the fuel vaporization member 10 at its end portion 11 the fuel is vaporized and these vapors rise into the burner pot 2 to be ignited by the ignition 18. After ignition of the fuel and the occurrence of continued combustion in the burner pot 2 the rod portion 12 of the fuel vaporization member 10 is heated to a temperature considerably above that at the hollow end portion 11 and heat therefrom is conducted down the member 10 to the hollow end portion 11 thereby raising the temperature of that portion above that maintained by the resistance heater 15. The thermostatic switch 46 is positioned adjacent the fuel well portion 3 and is responsive to the higher temperature of the hollow end portion 11 of the fuel vaporization member 10 when heated by the occurrence of combustion in the burner pot 2. When the hollow end portion 11 of the fuel vaporization member 10 reaches a sufficient predetermined temperature above that required for response by the switch 79, the thermostatic switch 46 will move opening the closed contacts 49 and 45, 48 and 51 and closing the open contacts 47 and 50. When the contacts 49 and 45 of the thermostatic switch 46 are opened the circuit for initial energization of the relay coil 33 is broken but the coil 33 continues to be energized by the aforementioned holding circuit. When the closed contacts 48 and 51 are opened the circuit through the resistance heater 15 and the ignition transformer 14 is broken thus de-energizing the resistance heater 15 and ignition 18 permitting the warp switch contacts 91 and 92 to open. The opening of the gas tube warp switch contacts 91 and 92 breaks the circuit through the fuel control valve 17 but the closing of the contacts 47 and 50 of the thermostatic switch 46 establishes a second circuit therethrough. With the closing of the contacts 47 and 50 a new circuit is established for energization of the fuel control valve 17 by way of conductor 84 leading from the fixed contact 47 of the thermostatic switch 46 to the control valve 17 which circuit is completed as before, the new fuel valve control circuit merely bypassing the warp switch 90.

In summation, it is seen that when the thermostat 25 closes calling for heat the relay switch 34 is energized thus establishing a circuit through the resistance heater 15 to heat the fuel vaporization member 10 for vaporization of fuel in the fuel well portion 3. Upon attainment of a predetermined temperature by the end portion 11 of the fuel vaporization member 10, the thermostatic switch 79 closes completing the circuit through the ignition transformer 14 at which time sparks occur in the burner and the ionizing electrode 93 is energized and the warp switch 90 is thus caused to close thereby establishing a circuit through the fuel supply control valve 17 to permit the flow of fuel to the fuel well portion 3. When fuel flows into the fuel well portion 3 and is vaporized by contact with the vaporization member 10, the fuel vapors rise into the burner

pot 2 where they are mixed with air supplied by the blower 7 and ignited by the ignition 18. Upon the occurrence of combustion in the burner pot 2 the rod portion 12 is heated by the flames in the burner pot and this heat is conducted to the hollow end portion 11 causing the temperature of the same to rise above that produced by the electrical resistance heater 15. Upon attainment of a second and higher predetermined temperature by the hollow end portion 11 of the fuel vaporization member 10 the thermostatic switch 46 is actuated causing the circuit to be broken through the resistance heater 15 and ignition transformer 14 and establishing a new circuit for energization of the fuel supply control valve 17. At this point in the operation the heat for the fuel vaporization member 10 is supplied by combustion in the burner pot 2 and the resistance heater 15 no longer being needed is de-energized. Correspondingly, the ignition 18 is de-energized. When the temperature of the space being heated rises sufficiently to satisfy the thermostat 25, the same will open thus de-energizing the relay switch 34 and breaking the circuit to the fuel supply control valve 17 shutting off the supply of fuel and permitting the system to return to its original initial condition upon cooling of the fuel vaporization member 10 and the thermostatic switches 46 and 79. Upon a subsequent calling for heat by the thermostat 25 the system will again function as heretofore described.

In the form of the invention shown in Fig. 2 the burner and fuel vaporization member and any of the parts of the control system therefor which are of similar construction to that shown in the form of the invention previously described and all parts common to both forms of the invention will bear common reference characters.

There is a burner 1 having a pot 2 with a fuel well portion 3 opening into the lower wall 9 thereof. The pot 2 has a plurality of holes 4 therein for the supply of combustion air and is surrounded by an air jacket 5^a having a cover member 6. The air jacket 5^a in this form of the invention is of slightly different construction from that shown in the previous form in that the jacketed air space also encloses the lower wall 9 of the burner pot 2 and there are a plurality of air supply holes 4^a in the lower wall 9 for the supply of combustion air underneath. As in the previous form of the invention there is a blower 7 for supplying combustion air to the jacketed space enclosed by the jacket 5^a and burner pot 2. There is a fuel vaporization member 10 having an enlarged hollow end portion 11 and a smaller solid rod portion 12 for vaporization of fuel supplied to the fuel well portion 3. There is a fuel supply conduit 13 which supplies fuel to the fuel well portion 3 through an aperture 14 in the lower outside wall portion thereof. The fuel vaporization member 10 has an electrical resistance heater 15 carried by a cylindrical insulating member 16 which is positioned inside the hollow end portion 11 thereof. The supply of fuel to the fuel well portion 3 is controlled by an electrically controllable valve 17 and the ignition of fuel in the burner pot 2 is accomplished by electrical spark ignition 18. There is an annular collar member 104 which fits over the rod portion 12 of the fuel vaporization member 10 and restricts the flow of fuel vapor into the burner pot 2 by providing a very narrow annular space for the discharge of fuel vapors for ignition from the fuel well portion 3. The collar member 104 also functions to heat fuel vapors com-

ing into the burner pot 2 to cause additional vaporization of any liquid particles entrained with the fuel vapors entering the pot. Electric current for the energization of the control system for this form of the invention is supplied from a main power source 19 to the primary 20 of a transformer 21. From the secondary 22 of the transformer 21 a conductor 23 runs to the fixed contact 24 of a room thermostat 25. The room thermostat 25 is of conventional construction having a fixed contact 24 and a movable contact 26 carried by a thermostatic bimetal blade 27. There is a compensating heater coil 28 for the thermostat 25 which is connected to the blade 27 and is in turn connected by a conductor 29 and resistor 30 to a connection point 31 on the transformer secondary 22. From the bimetal blade 27 of the thermostat 25 a conductor 32 runs to the coil 33 of a relay switch 34. The relay switch 34 has two pairs of fixed contacts 35 and 36 and two pairs of movable contacts 37 and 38. The movable contacts 37 and 38 are carried by contact arms 39 and 40 respectively which are connected each to each by an insulating member 41 for joint movement thereof. The relay coil 33 is connected by a conductor 42 to a connection point 43 on a conductor 44 which runs from the fixed relay contact 35 to a connection point 105 on a conductor 106 leading to a movable contact arm 107 of a thermostatic switch 108. The thermostatic switch 108 is carried by a bracket member 109 which is mounted on the lower wall 110 of the air jacket 5^a. The air jacket 5^a has an aperture 111 for the insertion of the helical bimetal actuating member 112 of the thermostatic switch 108 into the jacketed air space surrounding the burner pot 2. The thermostatic switch 108 has two contact arms 113 and 117 which are fixed to and actuated by a rod member 114 which is in turn operated by the helical bimetal element 112. In the thermostatic switch 108 there are three fixed contacts 115, 116 and 117 and three movable contacts 118, 119 and 120. The contacts 118 and 115, 119 and 116 are initially closed and the contacts 117 and 120 initially open so that movement of the thermostatic switch 108 will cause the two pairs of closed contacts to open and the one pair of open contacts to close. From the fixed contact 116 of the switch 108 a conductor 56^a runs to the connection point on a conductor 57 which interconnects the relay switch arm 39 and the connection point 31 on the transformer secondary 22. From the main power source 19 and connected in parallel circuit with the transformer primary 20 is a conductor 121 which runs to the fixed contact 36 of the relay switch 34. The relay switch arm 40 is connected by conductor 122 to the movable contact 118 of the thermostatic switch 108 and a conductor 123 connects the fixed contact 115 of the thermostatic switch 108 to the connection point 124 to which is connected the electrical resistance heater 15 which is in turn connected back to the main power source by a conductor 125. From the connection point 124 in the resistance heater 15 a conductor 126 runs to the primary 73 of an ignition transformer 74. The ignition transformer primary 73 is connected by a conductor 127 to one of the fixed contacts 128 of a thermostatic switch 129. The thermostatic switch 129 has two fixed contacts 128 and 130 and two movable contacts 131 and 132, the movable contacts being carried by contact arm 133. The thermostatic switch 129 is actuated by a bimetallic blade 134 which operates through the

insulating member 135 to move the contact arm 133. From the fixed contact 130 of the thermostatic switch 129 a conductor 136 runs to the motor 60 of the blower 7 which is connected to the main power source by a conductor 137. The contact arm 133 of the thermostatic switch 129 is connected to the main power source by a conductor 138. On the conductor 23 from the transformer secondary 22 there is a connection point 139 from which runs a conductor 140 to the electrically controllable fuel valve 17. The fuel valve 17 is connected at a connection point 141 to a conductor 142 which leads to the fixed contact 117 of the thermostatic switch 108. From the connection point 141 at the fuel valve 17 there is a conductor 143 which leads to the fixed contact 91 of a gas tube warp switch 90. The gas tube warp switch 90 has a bimetal blade member 89 on which is carried a movable contact 92 which cooperates with the fixed contact 91. The warp switch 90 has an ionizing electrode 93 which is connected to an induction coil 99. The bimetal contact arm 89 of the warp switch 90 is connected through its supporting member to the conductor 144 which leads to the connection point 105 where it joins the conductor 106 leading to the contact arm 107 of the thermostatic switch 108. The ignition transformer secondary 96 is connected at one end by a conductor 97 to an ignition electrode 98. From the other end of the ignition transformer secondary 96 is connected a pair of induction coils 99 and 109 which are grounded as at 101. The induction coil 100 is connected by a capacitance 102 to a connection point 103 on the conductor 97 leading to the ignition electrode 98.

In operation this form of the invention functions as follows:

When current is supplied from the main power source 19 the transformer 21 is energized for the control of the system. When the room thermostat 25 closes the circuit is completed from the transformer secondary 22 through the conductor 23, the closed thermostat contacts 24 and 26, and the conductor 32 to the relay coil 33. This circuit through the relay coil 33 is completed by conductors 42, 44, and 106, the closed contacts 116 and 119 of the thermostatic switch 108, and the conductors 56^a and 57 back to the connection point 31 on the transformer secondary 22. The circuit through relay coil 33 will cause the relay switch 34 to close. Upon closing of the relay contacts 35 and 37 a holding circuit for the relay coil 33 is established through the closed contacts 35 and 37 and the conductor 57 to the transformer secondary 22 which is independent of the circuit through the contacts of the thermostatic switch 108. When the relay contacts 36 and 38 are closed a circuit is completed from the main power source through the conductor 121, the closed relay contacts 36 and 38, the conductor 122, the closed thermostatic switch contacts 115 and 118, and the conductor 123 to the electrical resistance heater 15 which is connected back to the main power source by the conductor 125. It is thus seen that when the room thermostat 25 closes calling for heat the relay switch 34 is energized and closed and a holding circuit is established therefor. With the closing of the relay switch 34 the circuit is established from the main power source through the thermostatic switch 108 for the energization of the electrical resistance heater 15 which begins to heat the hollow end portion 11 of the fuel vaporization member 10. The thermostatic

switch 129 is positioned adjacent the fuel well portion 3 and is responsive to the temperature of the hollow end portion 11 of the fuel vaporization member 10. When the hollow end portion 11 of the member 10 reaches sufficient temperature the thermostatic switch 129 will move closing the contacts 128 and 131, 130 and 132 respectively thus establishing a circuit from the connection point 124 of the electric heater circuit by way of the conductor 126 to the ignition primary 73 and thence by conductor 127, the closed contacts 128 and 131, and conductor 138 leading back to the main power source 19. A circuit is also completed from the main power source 19 by conductor 137 to the blower motor 60 which is connected by conductor 136, the closed contacts 130 and 132, and conductor 138. Thus it is seen that when the electrical resistance heater 15 has heated the member 10 to a sufficient temperature to close the thermostatic switch 129 circuits are established energizing the ignition transformer 74 and the blower motor 60 in preparation for the supplying of fuel to the burner. As was described in the previous form of the invention when the ignition transformer 74 is energized and sparks occur in the spark ignition 18 the gas tube warp switch 90 is activated causing the contacts 91 and 92 to close. With the closing of the contacts 91 and 92 of the gas tube warp switch 90 a circuit is completed from the transformer secondary 22 by way of conductors 23 and 140 to the fuel valve 17 which is in turn connected by conductor 143 to the fixed contact 91 of the warp switch 90. From the warp switch 90 the circuit is completed back to the transformer secondary 22 by conductors 144 and 106, the closed contacts 116 and 119 of the thermostatic switch 108 and conductors 56^a and 57. At this point in the operation the electrical resistance heater 15 has heated the fuel vaporization member 10 to a sufficient temperature to vaporize fuel coming in contact therewith, the spark ignition 18 is functioning causing the occurrence of sparks in the burner pot 2 and the activation of the warp switch 90 has caused the circuit to the fuel valve 17 to be completed to open the same for the supply of fuel to the fuel well portion 3. When the fuel entering the fuel well portion 3 comes in contact with the vaporization member 10 it is vaporized and rises upward to the burner pot 2 where it mixes with the air supplied from the blower 7 and is ignited by the spark ignition 18. After ignition of the fuel vapors in the burner pot 2 the temperature of the air at the jacketed air space around the burner pot will rise above a predetermined value at which time the bimetal element 112 will cause the thermostatic switch 108 to move. Upon movement of the contact arms of the thermostatic switch 108 the contacts 116 and 119 are opened thus breaking the ignition circuit through the relay coil 33 which is however maintained by the holding circuit heretofore described and the opening of the contacts 115 and 118 will break the circuit through the heater coil 15 and the ignition transformer 74. When the contacts 120 and 117 of the thermostatic switch 108 are closed a second circuit is established for the energization of the fuel valve 17. This second fuel valve circuit runs from the transformer secondary 22 by way of conductors 23 and 140 to the valve 17 and by conductor 142, the closed contacts 117 and 120 of the thermostatic switch 108, the conductors 106 and 44, the closed contacts 35 and 73

37 of the relay switch 34, and the conductor 57, the circuit terminating back at the transformer secondary 22. In summation, it is seen that when the thermostat 25 closes calling for heat the relay switch 34 is energized and closed thereby energizing the heater coil 15. When the temperature of the fuel vaporization member 10 reaches a sufficient predetermined value the thermostatic switch 129 closes energizing the circuits through the blower motor 60 and the ignition transformer primary 73 thereby preparing the system for the ignition of fuel. Upon the occurrence of sparks at the spark ignition 18 in the burner pot 2 the gas tube warp switch 90 is activated thus completing the circuit for the energization of the fuel control valve 17 whereupon fuel is admitted to the fuel well portion 3. When the fuel admitted to the fuel well portion 3 is vaporized and ignited in the pot 2 the temperature of the jacketed air space surrounding the pot will rise causing the thermostatic switch 108 to open the contacts controlling the circuits to the heater coil 15 and the ignition transformer primary 73 thereby de-energizing the same and closing a circuit for continued energization of the fuel control valve. During combustion, as in the other form of the invention, heat for the vaporization of fuel entering the fuel well portion 3 at the hollow end portion of the vaporization member 10 is supplied by conduction from the rod portion 12 in the zone of combustion.

What is claimed and is desired to be obtained by Letters Patent of the United States is:

1. In a control system for a liquid fuel burner an electrically controllable valve for controlling the supply of fuel to said burner, heating means for vaporizing fuel in said burner prior to ignition thereof and including electrical heating means therefor, an electric spark ignition for said burner, means responsive to the generation of a predetermined temperature by said electrical heating means and operable to cause the energization of said ignition, means responsive to the occurrence of ignition sparks in said burner and operable to open said fuel supply control valve, means responsive to the occurrence of a predetermined temperature in said burner and operable to de-energize said ignition and said electrical heating means and to maintain said fuel supply control valve, relay switch means controlling energization of said system, a room thermostat controlling operation of said relay switch means, and said last-named responsive means including switch means opened by response to said predetermined temperature to prevent the initial energization of said relay switch means while said burner is hot.

2. In a control system for a liquid fuel burner, an electrically controllable valve for controlling the supply of fuel to said burner, a massive metallic member operable upon heating to vaporize fuel in said burner, an electrical resistance heater for said metallic member, electrically operable air supply means for said burner, an electric spark ignition for said burner, a circuit for said ignition, a thermostatic switch in said ignition circuit operable in response to the generation of a predetermined temperature by said heater to energize said ignition circuit, means including automatic switch means responsive to the occurrence of sparks in said burner and operable to energize said electrically controllable valve for opening movement thereof, a second thermostatic switch responsive to the occurrence of a pre-

determined temperature in said burner and operable to deenergize said ignition and said heater and to continue energization of said fuel supply control valve to hold the same open, means including a room thermostat for controlling energization of said system, and said last named thermostatic switch including switch contacts in series with said thermostat and operable to prevent initial energization of said system by said thermostat when the temperature in said burner is above a predetermined value.

3. A pot-type liquid fuel burner having a jacketed air space for supplying air to said burner and having a control system therefor comprising a controllable electric blower for supplying air to said jacketed air space, an electrically controllable valve for controlling the supply of fuel to the pot of said burner, a massive metallic member positioned in the pot of said burner and operable upon heating to vaporize fuel conducted thereagainst, an electrical resistance heater for said metallic member, an electric spark ignition for said burner, circuits for said ignition and said blower, a thermostatic switch closable in response to the generation of a predetermined temperature by said heater to energize said ignition and said blower circuits, means including automatic switch means responsive to the occurrence of ignition sparks in said burner and operable to energize said electrically controllable valve for opening movement thereof, a second thermostatic switch positioned in said jacketed air space and responsive to the occurrence of a predetermined temperature in said burner and operable to deenergize said ignition and said heater and to continue energization of said fuel supply control valve to hold the same open, means including a room thermostat for controlling energization of said system, and said last named thermostatic switch including switch contacts in series with said thermostat and operable to prevent initial energization of said system by said thermostat when the temperature in said burner is above a predetermined value.

4. A control system for a liquid fuel burner having a jacketed air space for supplying air to said burner comprising a burner pot having a fuel well portion, a controllable electric blower for supplying air to said jacketed air space, an electrically controllable valve for controlling the supply of fuel to said fuel well portion, a massive metallic member positioned in said fuel well portion and extending upward through said pot and operable upon heating to vaporize fuel supplied to said fuel well portion, an electrical resistance heater for said metallic member, an electric spark ignition for said burner, circuits for said ignition and said blower, a thermostatic switch positioned adjacent said fuel well portion and closable in response to the generation of a predetermined temperature by said heater to energize said ignition and said blower circuits, means including an automatic switch responsive to the occurrence of electrical ignition sparks in said burner and operable to energize said electrically controllable valve for opening movement thereof, a second thermostatic switch positioned in said jacketed air space and responsive to the occurrence of a predetermined temperature in said burner and operable to de-energize said ignition and said heater and to continue energization of said fuel supply control valve to hold the same open, relay switch means controlling energization of said system, a room thermostat controlling energization of said relay switch means, and said last named thermostatic switch including switch contacts in series with said room thermostat and controlling energization of said relay switch means,

5 and said last-named thermostatic switch including switch contacts in series with said room thermostat and operable to prevent initial energization of said relay switch means while the temperature of said burner is above said predetermined temperature.

10 5. A control system for a liquid fuel burner comprising a burner pot having a fuel well portion, a constantly running electric blower for supplying air to said pot, an electrically controllable valve for controlling the supply of fuel to said fuel well portion, a massive metallic member positioned in said fuel well portion and extending upward through said pot, an electrical resistance heater for said metallic member, said metallic member being heated initially by said heater and subsequently by flame in said pot and being operable upon said heating to vaporize fuel in said fuel well portion, an electric spark ignition for said burner, an electric circuit for said ignition, a thermostatic switch positioned adjacent said fuel well portion and closable in response to the generation of a predetermined temperature by said heater to energize said ignition, circuit means including automatic switch means responsive to the occurrence of electrical ignition sparks in said burner and operable to energize said electrically controllable valve for opening movement thereof, a second thermostatic switch positioned adjacent said fuel well portion and responsive to the temperature of said metallic member when heated by the occurrence of flame in said pot and operable to deenergize said ignition and said heater and to continue energization of said fuel supply control valve to hold the same open, relay switch means controlling energization of said system, a room thermostat controlling energization of said relay switch means, and said last named thermostatic switch including switch contacts in series with said room thermostat and controlling energization of said relay switch means.

15 6. In a liquid fuel burner and control system therefor, a vaporizing pot, electrically controlled means for supplying fuel to said pot, a metallic member positioned in said pot and extending upward into the zone of combustion and operable upon heating to vaporize fuel entering said pot, electrical means operable upon energization to heat said metallic member for initial operation, said metallic member being subsequently heated by flame after the occurrence of the same in said pot, means responsive to the heat of flame in said pot and operable to de-energize said electrical heating means, means including a room thermostat for controlling energization of said system, and said last-named responsive means including switch means connected in series with said thermostat and operable to prevent initial energization of said system by said thermostat so that said fuel supply means may not be energized while the temperature of said burner pot is in excess of a predetermined value.

20 7. A liquid fuel burner having a vaporizing pot, a fuel well opening upwardly into said pot, a metallic member having an enlarged hollow end portion and a solid rod end portion for conducting heat to said hollow end portion, said enlarged hollow end portion being positioned in said fuel well and forming with the walls of said fuel well an annular space of small cross section, said solid rod end portion extending upwardly through said pot into the zone of combustion, said metallic member being operable upon heating to vaporize fuel in said annular space, an

electrical resistance heater in said hollow end portion and operable upon energization to heat the same for initial operation, said hollow end portion being heated by conduction of heat from said solid rod portion after the occurrence of combustion in said pot, means responsive to the heat of combustion in said pot and operable to de-energize said electrical resistance heater, an electrically operated valve controlling the supply of fuel to said burner, electric circuit means for controlling said valve, means including a room thermostat controlling energization of said electric circuit means, and said responsive means including switch means connected in series with said room thermostat and operable to prevent initial energization of said electric circuit means by said room thermostat when the temperature of said burner pot is in excess of a predetermined value.

8. In a control system for a liquid fuel burner, electrically operated means for controlling the supply of fuel to said burner, a fuel vaporizing member having an electric heating coil and operable to vaporize fuel prior to ignition thereof, an electric spark ignition in said burner and having an energizing transformer; electric circuits for said fuel supply means, said electric heating coil, and said transformer; a thermostatic switch in said transformer circuit and operable to energize said ignition in response to heat of said heating coil, means in said fuel supply circuit responsive to the occurrence of sparks in said burner and operable to actuate said fuel supply means, a single pole double throw switch having a pair of initially closed contacts in a portion common to said ignition transformer circuit and said heating coil circuit, a second circuit for said fuel supply means independent of said spark responsive means, said last-named switch having a pair of initially open contacts in said second fuel supply circuit; thermostatic means responsive to the heat of combustion in said burner and operable to move said last-named switch to deenergize said ignition and said heating coil circuits, and to energize said second fuel supply means circuit; a relay switch having a pair of initially open contacts in series with the movable pole of said last-named switch, an en-

ergizing circuit for the coil of said relay switch, a room thermostat in said relay coil circuit, an initially closed switch in said relay coil energizing circuit and operated by said combustion responsive thermostatic means, and circuit means including a switch closed upon energization of said relay coil to shunt said last named switch.

9. In a control system for a liquid fuel burner, means for controlling the supply of fuel to said burner, means for vaporizing fuel in said burner prior to ignition thereof and including electrical energization means therefor, electrical means for igniting fuel in said burner, means responsive to the heating of said fuel vaporization means and operable to control the energization of said fuel supply controlling means, means responsive to the heat output of said burner and operable to de-energize said ignition means and said fuel vaporization means, a relay switch having a coil and circuit therefor and having contacts controlling energization of said system, a room thermostat controlling energization of said relay coil, switch means in said relay coil circuit and opened by said last-named responsive means to prevent initial energization of said system by operation of said thermostat while said burner is above a predetermined temperature, and said relay switch having contacts connected in parallel with said last named switch means to provide a holding circuit for said relay coil during normal operation of said burner.

FRED B. AUBERT.
